UNITED STATES PATENT OFFICE

JOHN J. GOTTSCHALK, OF TAUNTON, MASSACHUSETTS

SHAVING BRUSH

Application filed January 26, 1931. Serial No. 511,148.

My present invention relates to brushes and particularly shaving brushes and aims to provide an improved device of the class described and wherein a self-contained 5 renewable supply of liquid soap is included.

In the drawing, illustrating by way of example one embodiment of the invention,

Figure 1 is a central vertical section through a complete brush, with the parts in 10 feeding position;

Fig. 2 is a view similar to Fig. 1 but with the parts in non-feeding position;

Fig. 3 is a vertical section of the liquid-containing handle as a separate article of 15 manufacture and sale;

Fig. 4 is a plan of the handle; and

Fig. 5 is a bottom or inside plan view of the bristle holder, with the handle removed, and as viewed from below in Figs. 1 or 2.

20 In the illustrative embodiment of the invention here shown, the brush includes a bristle portion 1, the bristles of which are anchored in a tubular holder 2 a suitable composite or other material. At an intermediate point the holder is formed with an internal partition 3, dividing it into two

25 socket-like portions and closing off the inner or bottom ends of the bristles. The partition 3 carries at its face adjacent the bristles a substantially axial tube or nozzle 4 extending into the body of bristles and having a through passage 5 of appropriate diameter affording communication between the lower socket portion of the bristle holder and the

30 bristles themselves.

At the opposite or lower side of the partition 3 is a nipple 6, preferably having a tapered outer surface substantially as illustrated, and centrally apertured in prolongation of the passage 5 in the nozzle. The lower socket portion of the bristle holder, as positioned in Figs. 1 and 2, is internally threaded, as indicated at 7.

35 For cooperation with the described bristle holding element I provide a handle portion in the form of a container for liquid soap or the like. Its construction and arrangement, as illustrated, are such that a user after once purchasing the complete outfit consisting of the brush holder and the soap-filled

reservoir or handle, may upon depletion of the soap supply, renew it by substituting a duplicate or "refill" soap-containing handle, manufactured and purchasable as a separate article.

55

Referring now to Figs. 3 and 4, the reservoir or containing handle 10 is desirably of a hollow tubular form substantially as illustrated, having a flat base 11 upon which it may be stood upright and being shaped in a

60

manner convenient to the hand of the user. It is preferably formed of a transparent material of suitable rigidity, such as glass or a transparent composition, so that the quantity and condition of the soap supply S may readily be observed. At its upper portion is an exteriorly threaded shoulder 12, above which is a neck 13 of slightly reduced diameter, terminating in an overhanging annular lip 14. The container is normally closed by a

65

cap 15, preferably of rubber or like yielding elastic material having a lower inturned flange 16 adapted to seat below the lip 14 of the container and to engage tightly about the neck 13 of the latter. The cap is constituted

70

as a valve, being provided for that purpose with a thin central diametral slit 17. The construction of the cap 15 and its valve slit 17 is such that the latter is self-closing and normally retains the liquid contents, except

75

when forced open in a manner to be described. Preferably the central area 18 of the cap 15, wherein the valve slit is formed, is made somewhat thinner or more elastic than the contiguous outer portion of the cap, insuring

80

an easy and certain opening and closing action, functioning somewhat in the manner of a diaphragm. While I have shown as a preferred construction internal threads on the brush holder and external threads on the handle or container, obviously a reverse construction could be employed within the scope of my invention.

85

In Fig. 2 the parts are shown in their normal position, wherein the soap supply is shut off. The containing handle is then turned up but part way with respect to the threaded portion 7 of the bristle holder, the valve cap 15 being spaced from or barely in contact with the end of the nipple 6. When it is

90

95

100

desired to obtain a charge of soap, as for creating a lather for shaving purposes, it is but necessary to turn the handle and the brush portions inwardly or together, with respect to each other, to such predetermined extent as to cause the nipple to enter and spread the valve slit 17 of the container cap, substantially as shown in Fig. 1. The desired quantity of the liquid soap can then flow to the bristles, through the passage 5 of the nozzle 4. Inasmuch as the brush as a whole is constructed to stand upright, by reason of the flat base 11, the parts may be left in their feeding position of Fig. 1 during periods of non-use, or the handle 10 may be backed off into the position of Fig. 2, again completely and automatically closing off the soap supply. When the soap supply has been exhausted the reservoir or handle 10 may quickly be detached and discarded. The brush portion remains in instant readiness for reception of a fresh container-handle with its soap supply, without requiring special manipulating of either of the parts.

It will be observed that the soap flow is possible only when the handle element is turned well down into the holder and is shut off at all other times. Thus the natural tendency of the parts to unscrew with respect to each other is taken advantage of as tending to insure the closing off of the feed at such times as it is not desired. It will also be understood that in bringing the handle and holder portions together, by turning them up relative to each other, to admit soap to the bristles, the diaphragm-like structure of the cap as illustrated will assist to cause a charge of soap to be forced through the nozzle 4, by reason of the attendant depression of the cap by the nipple 6 prior to and while opening the valve slit 17, pressure being thereby applied to the liquid contents or to any air in the container, thus affording a force-feed action. The provision of the more elastic or thinner central area 18 for the cap augments this positive feed effect.

My invention is not limited to the particular embodiments thereof herein shown and described, its scope being pointed out in the following claims:

I claim:

1. A shaving brush comprising, in combination, a brush holder having opposed socket portions separated by a partition, a body of bristles anchored in one socket portion, the other socket portion being threaded, a tubular member providing a passage between the socket portions, terminating at one end within the body of bristles and at its opposite end forming a nipple projecting into the other socket portion, a hollow handle having a portion threaded for cooperation with the threaded socket of the brush holder, and a closure cap at the inner end of the handle having a self-closing valve

operable by the projection of said nipple into opening relation with it.

2. A shaving brush comprising, in combination, a hollow handle portion adapted to hold a supply of liquid soap, a brush holder 70 provided with a body of bristles, said handle and holder having threaded formations for adjustably uniting and disconnecting them, partitioning means in the holder at the base of the bristle body, a nipple projecting oppositely from the bristle body and communicating therewith, and a closure member at the inner end of the handle, having a self-closing valve formation adapted to be 80 opened by projecting said nipple into it thereby to permit a flow of soap from the handle into the body of bristles. 75

3. A shaving brush comprising, in combination, a hollow handle portion adapted to hold a supply of liquid soap, a brush 85 holder provided with a body of bristles, said handle and holder having threaded formations for adjustably uniting and disconnecting them, partitioning means in the holder at the base of the bristle body, a nipple projecting oppositely from the bristle body and communicating therewith, and a rubber cap 90 closing the inner end of the handle and having a self-closing valve aperture in operative relation to the nipple of the holder. 95

4. In a shaving brush, in combination; a tubular holder having an internal partition; a body of bristles fixed in the holder to one side of said partition, the latter having an approximately central nozzle extending into 100 the body of bristles and having an oppositely extending nipple communicating with the nozzle; and a hollow handle portion constituting a liquid container, said handle and brush holder portions constructed for screw-threaded interengagement, the handle having at one end a neck portion and a rubber cap fitted to and closing the neck portion, said cap provided with a self-closing valve formation positioned to be opened by the 105 nipple of the brush holder when the parts are screwed together to a predetermined extent. 110

5. As a new article of manufacture, a liquid soap container of transparent material 115 and formed to constitute the handle of a shaving brush, said container being closed at one end and having at its opposite end a threaded portion and an integral neck of smaller diameter than said threaded portion, 120 and a cap fitted on and held by the neck portion, said cap having a self-closing valve formation at its central area, whereby the container is closed at said opposite end, independently of other structure, and is adapted 125 to constitute a separate article or package.

6. As a new article of manufacture, a hollow handle for a shaving brush, formed of transparent rigid material and adapted to hold a supply of liquid soap, said handle 130

having at one end a threaded portion for adjustably attaching it to a brush holder and having also at said end an integral closure-supporting neck, and a closure element in the general form of a diaphragm seated on and closing said neck and having a substantially central self-closing integral valve formation said handle being constituted as a complete holder for soap independently of other parts.

7. As a new article of manufacture, a hollow handle for a shaving brush, formed of transparent rigid material and adapted to hold a supply of liquid soap, said handle having at one end a threaded portion for adjustably attaching it to a brush holder and having also formed on said end an integral closure-supporting neck, and a rubber cap affixed to said neck and having an approximately central diametral slit formation constituting a self-closing valve.

8. As a new article of manufacture, a hollow handle for a shaving brush, formed of transparent rigid material and adapted to hold a supply of liquid soap, said handle having at one end a threaded portion for adjustably attaching it to a brush holder and having also formed on said end an integral closure-supporting neck, and a rubber cap affixed to said neck and having an approximately central diametral slit formation constituting a self-closing valve, the portion of said cap containing and immediately surrounding said slit formation having a greater elasticity than the contiguous outer portion of the cap.

9. As a new article of manufacture, a hollow handle for a shaving brush, formed of transparent rigid material and adapted to hold a supply of liquid soap, said handle having at one end a threaded portion for adjustably attaching it to a brush holder and having also formed on said end an integral closure-supporting neck, and a rubber cap affixed to said neck and having an approximately central diametral slit formation constituting a self-closing valve, the rubber material of the central cap portion containing said slit formation being thinner than the contiguous outer portion.

In testimony whereof, I have signed my name to this specification.

JOHN J. GOTTSCHALK.
